DESIGN FOR A SLIP

Harry Diamond, Cedarhurst, N. Y.

Application January 15, 1938, Serial No. 74,316

Term of patent 3½ years

To all whom it may concern:

Be it known that I, Harry Diamond, a citizen of the United States, residing in Cedarhurst, county of Nassau, and State of New York, have invented a new, original, and ornamental Design for a Slip, of which the following is a specification, reference being had to the accompanying drawing, forming part thereof.

I claim:

The ornamental design for a slip as shown and described.

HARRY DIAMOND.
